UNITED STATES PATENT OFFICE.

CHARLES EDWARD FISHER, OF FREDERICK, MARYLAND, ASSIGNOR TO THE AMERICAN FOUNDRY & MANUFACTURING COMPANY, OF FREDERICK, MARYLAND, A CORPORATION OF MARYLAND.

DESIGN FOR A FEED-TROUGH.

44,440.

Specification for Design.

Patented Aug. 5, 1913.

Application filed January 28, 1913. Serial No. 744,771. Term of patent 7 years.

To all whom it may concern:

Be it known that I, CHARLES EDWARD FISHER, a citizen of the United States, residing at Frederick, in the county of Frederick and State of Maryland, have invented a new, original, and ornamental Design for a Feed-Trough, of which the following is a specification, reference being had to the accompanying drawing, forming part thereof.

In the drawing herewith:—Figure 1 is a perspective view of a trough made in ac-

cordance with my design. Fig. 2 is a view in side elevation of the trough shown in Fig. 1.

I claim:

The ornamental design for a feed trough as shown.

CHARLES EDWARD FISHER.
